UNITED STATES PATENT OFFICE.

WILLIAM A. COOKE, JR., OF NEW YORK, N. Y.

LETTER-FILE OR THE LIKE.

1,107,657.

Specification of Letters Patent. Patented Aug. 18, 1914.

Application filed March 17, 1903. Serial No. 421,676.

To all whom it may concern:

Be it known that I, WILLIAM A. COOKE, Jr., a citizen of the United States, residing in the borough of Brooklyn, county of 5 Kings, city and State of New York, have invented certain new and useful Improvements in Letter-Files or the like, of which the following is a specification.

This invention relates to letter files, temporary binders and other similar devices 10 of the type in which prongs or like filing members are provided for receiving the papers filed. In this type of binder some means for perforating the papers is practically necessary. Such means having usually 15 taken the form of separate perforators adapted to cut a single hole in the paper, the eye being used as a guide to secure the proper distance between the several holes corresponding to the number of prongs. 20 Such perforating or puncturing devices have the disadvantage of being more or less expensive, and the still greater disadvantage of being separate from the files so that 25 they are not always at hand when required. They have the additional disadvantage that it is difficult to judge the distance between the prongs so that papers are often punctured or perforated inaccurately. While it 30 is possible with very stiff prongs to force a single sheet of paper over them and to thus avoid the necessity of perforating the papers prior to filing, this method is apt to tear the paper, and is open to the further 35 objection that as the ends of the prongs are usually a considerable distance above the file it is difficult to puncture the papers at the proper points so that they will lie evenly in the file. This method of puncturing the 40 papers is practically impossible in the case of binders of the type set forth in patents to Dow for instance, Nos. 849,774 and 849,836, wherein the prongs are adapted to be bent over to retain the papers in place, 45 and to be bent upwardly to receive fresh papers. Such prongs can rarely be bent so accurately that their upper or pointed ends are the same distance apart as their bases so that if the paper to be filed could be 50 punctured directly by the prongs, the positions of the holes would vary from that which they should occupy when the paper

is moved down to the bases of the prongs. Moreover, with easily bendable prongs of this type sufficient stiffness is not afforded 55 to force down the papers over the ends of the prongs.

According to my invention I provide a file or other similar device (which I will hereinafter refer to as a file) which has 60 formed in it or carries with it a device which in effect constitutes a puncturing means for the papers. Such puncturing device according to my invention is preferably 65 adapted to form in the paper to be filed a number of holes which correspond to the number of prongs contained in the binder, such holes being spaced apart a distance corresponding to that between the prongs. The puncturing means is preferably so located 70 that some part of the file or cover will serve as an indicating means whereby the paper to be filed may be so adjusted that it will occupy the proper position within the file after being placed on the prongs. 75

My invention in its broadest form comprises a file having an aperture or apertures in its cover or other suitable part over which the paper may be placed, and through which and the paper a pencil, pen holder 80 or other suitable device may be passed to perforate the paper. It is practically essential that such perforations shall be so located with relation to the other parts of the binder that there shall be sufficient room 85 for the pencil to extend a considerable distance through the perforations. Otherwise a puncture of sufficient diameter cannot be made through the paper.

My invention also includes other features 90 of construction which will be hereinafter referred to.

Referring to the drawings which illustrate several forms of the invention, Figure 1 is a plan view of a file with the invention 95 applied thereto, the file being shown as open. Fig. 2 is a section of Fig. 1 on an enlarged scale, the view being taken on the line 2-2 in Fig. 1, and the file being shown as closed. Fig. 3 is a detail view illustrating the method of puncturing the paper. Fig. 4 is a plan view of a modification. Fig. 5 is a detail similar to Fig. 3. Fig. 6 is an end view of the back part of the

binder. Fig. 7 is a sectional view of a modification.

In the drawings I have illustrated a file of the type set forth in the patents to Dow 5 above referred to, wherein are provided two covers A and B having a back C which is folded at its middle as shown at *a* to provide what is in effect a hinge for the covers. Guards or flaps *b c* are provided, the lower 10 of which *c* carries a plurality of flexible prongs *d d'* which are designed to pass through perforations in the papers filed, and the upper of which is formed with slots *e e'* which are designed to receive the prongs 15 as the upper guard is moved into position over the rear edges of the papers. The prongs are then bent over by hand along the upper surface of the guard *b* (as shown at *d'*, Fig. 1) and clamps such as *f f'* are 20 swung rearwardly so that they pass over the tops of the bent prongs and hold the latter securely in place. This type of file is of very cheap construction, and has the advantage that its clamping mechanism takes up little 25 room so that the total thickness of the binder is very little in excess of the combined thicknesses of the covers and the filed papers between them. This results in an important 30 advantage in that the file requires a very small storage space when it contains few papers, and that such storage space is the practical minimum required for the bulk of papers inclosed in the file. It is practically impossible in this type of file to 35 provide a perforating mechanism without neutralizing this important advantage. According 40 to my invention, however, I provide this or any other type of file with a puncturing device, as distinguished from a perforating mechanism, which does not in any way increase the bulk of the file, which is extremely cheap and efficient, and which has the great advantage that it can never be lost or mislaid so that it is always at hand in use 45 of the file.

Fig. 4 shows my device in its simplest form. In this figure one of the covers of the binder is provided with two holes or apertures *D D'*. These holes or apertures 50 are preferably placed opposite the binding prongs *d d'*, and are spaced apart the same distance as the bases of such prongs. In use the paper to be filed is placed in position over the holes, and a pencil or other pointed 55 instrument is forced through the paper and holes, providing a well defined puncture through which the prongs are capable of easily passing when the paper is filed. The 60 holes or apertures *D D'* not only form a guide for determining the distance between the punctures, but their edges provide a forming means adapted to coact with the pencil or other instrument so as to provide a well defined and rounded puncture which is 65 not liable to tear. Even though the holes

D D' in this construction are hidden by the sheet to be perforated, their position can easily be ascertained by the finger of the user. Preferably the holes are provided with eyelets so as to prevent their enlargement from repeated use.

The position of the holes *D D'* is of importance. Preferably they are not only spaced apart the same distance as the prongs, but are also so arranged that the sheet may 75 be perforated at the proper positions desirable for the particular binder to which the invention is applied. In the construction of Fig. 4 the guard *b* has a definite line of bending with relation to the cover A, such 80 line being indicated by the letters *x x* in Fig. 4. It has also a similar line of bending with relation to the back C, shown at *y* in Fig. 6. Preferably the apertures *D D'* are located such a distance from the line *x x* that when 85 the sheet to be perforated is brought with its edges near such line, the perforations will be at such a distance from the rear edge of the sheet that such rear edges can be easily accommodated within the binder. Fig. 6 90 shows the binder practically full, and illustrates the position of such rear edges. Preferably also some part of the binder, such as the top or bottom edges of the cover, is utilized as a guide to indicate the proper 95 points for the perforations. Thus in Fig. 4 either the top or bottom edge of the cover serves as a guide which shows the position that the sheet (marked X) will occupy after being perforated and bound.

While the holes *D D'* may be placed in any desired part of the device, it is practically essential that they should be so located and formed as to permit the point of a pencil or other puncturing instrument to 105 extend a considerable distance into the hole past the sheet being perforated. Practically speaking, the puncturing instrument must be provided with a point, and taper to a larger diameter in order to obtain a satisfactory puncturing effect. This requires a 110 relatively extensive movement of the puncturing instrument as compared with the thickness of the sheet being perforated. When the holes *D D'* are placed in the cover, the puncturing instrument may, of course, 115 pass out of the opposite side. If they are otherwise located provision will preferably be made for a like extension.

In Fig. 4 I have also shown another arrangement of puncturing apertures. In this case the apertures are lettered *D⁴ D⁵*, and are located near the edge of one of the covers. Preferably two lines *j j* are drawn outwardly from the perforations, which 125 lines either join or extend beyond the line *k*. Suitable pointers are preferably arranged to indicate the positions of the perforations *D⁴ D⁵* or lines *j*. In this construction the paper is placed over the perforations along

the line *k*, and while held in such position it is punctured by the puncturing instrument. The pointers *l* indicate with sufficient clearness the positions of the perforations so that there is no difficulty in finding them with the instrument.

In Figs. 1 and 2 I have shown my invention in another form. In these figures I provide a metal plate *F* bent to approximately **U**-form, one side of which is fastened to the cover or other part of the binder, and the other side of which is separated therefrom so that the papers may be passed between the two. Both sides of the plate are **15** perforated and the lower side *g* (Fig. 3) is preferably united to the cover by means of eyelets. The upper perforations *D*² *D*³ are preferably somewhat larger than the lower perforations so that the eyelets may pass **20** through the former in process of attaching the plate. In use the rear edge of the sheet is slipped under the upper side *h* of the plate, until it contacts with the bend of the latter, and the puncturing instrument *I* is **25** passed through both the sheet of paper and the cover as shown in Fig. 3. In this construction the holes in the upper plate *h* serve to indicate the points at which the paper is **30** to be punctured and serve also to guide the puncturing instrument. This construction has the important advantage that the position of the perforations is always plainly indicated. Obviously any other means for **35** effecting this result may be used. The plate *F* with its holes may be located at any desired point upon the file, but preferably it is so located and formed that the punctured holes are made at the proper points in the sheet, both with relation to its rear edge **40** and its top and bottom edges to insure that the sheet shall assume a proper position within the file. The plate *F* may be made of any desired material, such as metal, pasteboard, or the like, but is preferably sufficiently flexible to enable the user to clamp **45** the paper in place with one hand during the puncturing operation.

In Fig. 7 I have shown a form similar to that of Fig. 1 in which the member *F'* is **50** made of pasteboard or other flexible material, the lower side of which is eyeleted to the cover and the upper side of which is adapted to fold back to the dotted line position of this figure. This permits the member *F'* to be folded along the inner side of the cover when not in use so that it is substantially only half as thick as would otherwise be the case.

Although I have shown in detail several **60** forms of my invention I do not wish to be limited thereto as various modifications may be made therein without departing from the invention. For instance, in place of the holes or apertures *D* *D'* any other means **65** may be used which will accomplish the same

result, and such means are intended to be covered by the term "apertures" as used in the claims. While my invention finds its chief field of usefulness with a file of the type illustrated, it is nevertheless adapted **70** for use with other types of files.

The specific form of the invention wherein the apertures *D* *D'* are located adjacent the inner edge of the cover and adjacent the guard flap, is described and claimed in a **75** divisional application, filed March 8, 1911, Serial No. 613,024.

What I claim is:—

1. A binder or file for sheets of paper or the like, comprising fastening means for the **80** sheets, a cover, apertures in said cover spaced apart a distance equal to the distance between said fastening means, and a strip of flexible material, attached to said cover and having apertures therein spaced apart a distance corresponding to that of the apertures in the cover, adapted to be bent over a sheet of paper and clasp the same with the apertures therein registering with those in the cover, said cover being substantially flat and **85** unobstructed and forming a supporting surface for receiving a sheet to be punched and filed, said apertures and cover being constructed to permit the edge of the sheet to lie over said apertures while its body is supported on said cover.

2. A binder or file for sheets of paper or the like, comprising fastening means for the sheets, a cover, apertures in said cover spaced apart a distance equal to the distance **100** between said fastening means, and a strip of flexible material, attached to said cover, having apertures therein spaced apart a distance corresponding to that of the aperture in the cover, and of a width such that **105** when bent to clasp a sheet of paper it will limit the distance said sheet lies over said aperture to approximately the distance between said fastening means and the back of the binder, the apertures therein registering **110** with those in the cover, said cover being substantially flat and unobstructed and forming a supporting surface for receiving a sheet to be punched and filed, said apertures and cover being constructed to permit **115** the edge of the sheet to lie over said apertures while its body is supported on said cover.

3. A binder or file for sheets of paper or the like, comprising fastening means for the **120** sheets, a cover of fibrous material, apertures in said cover spaced apart a distance equal to the distance between said fastening means, and eyelets in said apertures of a size to admit the partial insertion of the point of a **125** pencil therein, said cover being substantially flat and unobstructed and forming a supporting surface for receiving a sheet to be punched and filed, said apertures and cover being constructed to permit the edge of the **130**

sheet to lie over said apertures while its body is supported on said cover.

4. A binder or file for sheets of paper or the like, comprising fastening means for the sheets, a cover, apertures in the left-hand side of said cover spaced apart a distance equal to the distance between said fastening means, and a strip of flexible material, attached also to the left-hand side of said cover and having apertures therein spaced apart a distance corresponding to that of the apertures in the cover, adapted to be bent over and clasp a sheet of paper with the apertures therein registering with those in the cover, said cover being substantially flat and unobstructed and forming a supporting surface for receiving a sheet to be punched and filed, said apertures and cover being constructed to permit the edge of the sheet to lie over said apertures while its body is supported on said cover.

5. A binder or file for sheets of paper or the like, comprising fastening means, apertures in said binder spaced apart a distance equal to the distance between said fastening means, and a strip of flexible material having apertures therein spaced apart a distance equal to the apertures in said binder, adapted to be bent to clasp a sheet of paper over the apertures in said binder, whereby the sheet of paper may be held while having holes punched therein.

6. A binder or file for sheets of paper or the like, comprising fastening means, apertures in said binder spaced apart a distance equal to said fastening means, and a strip of flexible material, said flexible strip being adapted to be pressed into engagement with a sheet of paper and clasp the same over the apertures in said binder and limit the extent which the sheet of paper projects over said apertures, whereby the sheet may be held while having holes punched therein and have the holes punched a regular distance from its edge.

7. A binder or file for sheets of paper or the like comprising fastening means, apertures in said binder spaced apart a distance equal to the distance between said fastening means, and a strip of flexible material folded upon itself and having apertures therein spaced apart a distance equal to the space between the apertures in said binder, said folded flexible strip being adapted to be pressed into engagement with a sheet of paper and clasp the same over the apertures in said binder and limit the extent which the sheet of paper projects over said apertures, whereby the sheet may be held while having holes punched therein and have the holes punched a regular distance from its edge.

8. A binder or file for sheets of paper or the like having fastening means, and adapted to pass through holes in the paper sheets,

and said binder having apertures spaced apart a distance equal to the distance between said fastening means, and a clamping member adapted to extend over the paper sheets to clamp them against the binder, said member being connected to the binder so that its free edge opens toward the major part or greater expanse of the latter whereby the paper sheets rest upon the binder when clamped, and said member having indicating provisions coinciding with the apertures of the binder whereby to guide the user in passing a pointed instrument through said paper sheets and apertures.

9. A binder or file for sheets of paper or the like having fastening means, and adapted to pass through holes in the paper sheets, and said binder having apertures spaced apart a distance equal to the distance between said fastening means, and a clamping member adapted to extend over the paper sheets to clamp them against the binder, said member being connected to the binder so that its free edge opens toward the major part or greater expanse of the latter whereby the paper sheets rest upon the binder when clamped, and said member having apertures coinciding with the apertures of the binder whereby to guide the user in passing a pointed instrument through said paper sheets and apertures.

10. A file or the like, having fastening means adapted to pass through the paper at a plurality of points, and having a cover forming a support for a paper sheet to be perforated, the cover having a part provided with apertures, adapted to admit a pencil or the like to perforate the paper sheet, said apertures lying under the paper sheet when the latter is supported on the cover, and indicating means for indicating the positions of the apertures when the latter are covered by the paper sheet.

11. A file or the like, having fastening means adapted to pass through the paper at a plurality of points, and having a cover forming a support for a paper sheet to be perforated, the cover having a part provided with apertures near one of the edges of the cover, adapted to admit a pencil or the like to perforate the paper sheet, said apertures lying under the paper sheet when the latter is supported on the cover, and indicating means for indicating the positions of the apertures when the latter are covered by the paper sheet.

12. A file or the like, having fastening means adapted to pass through the paper at a plurality of points, and having a cover forming a support for a paper sheet to be perforated, the cover having a part provided with apertures near one of the edges of the cover, adapted to admit a pencil or the like to perforate the paper sheet, said apertures lying under the paper sheet when

the latter is supported on the cover, and indicating means provided with apertures aligned with those of the cover for indicating the positions of the apertures of the cover 5 when the latter are covered by the paper sheet.

In witness whereof, I have hereunto

signed my name in the presence of two subscribing witnesses.
